(57) **CLAIM**

The ornamental design for a lighting device, as shown and described.

DESCRIPTION

FIG. 1 is a top front perspective view of a lighting device shown in an environment of use.

FIG. 2 is a bottom rear perspective view of the lighting device of FIG. 1 shown with the environment removed for clarity of disclosure.

FIG. 3 is a front view of the lighting device of FIG. 2.

FIG. 4 is a back view of the lighting device of FIG. 2.

FIG. 5 is a left side view of the lighting device of FIG. 2.

FIG. 6 is a right side view of the lighting device of FIG. 2.

FIG. 7 is a top view of the lighting device of FIG. 2, and,

FIG. 8 is a bottom view of the lighting device of FIG. 2.

The broken lines immediately adjacent the shaded areas depict the bounds of the claimed design, while all other broken lines are directed to environment and are for illustrative purposes only; all broken lines form no part of the claimed design.

1 Claim, 5 Drawing Sheets
